(57) **CLAIM**

The ornamental design for a charger as shown and described.

DESCRIPTION

FIG. 1 is a front, right and top perspective view of a charger, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the charger, shown in an environment.

In the drawings, the broken lines depict portions of the charger that form no part of the claimed design. In FIG. 9, the broken lines also show environment that form no part of the claimed design.

1 Claim, 9 Drawing Sheets
